UNITED STATES PATENT OFFICE.

ALOIS ALLMUTH, OF NEW YORK, N. Y.

PEDAL REED-ORGAN ATTACHMENT FOR ORGANS OR PIANOS.

SPECIFICATION forming part of Letters Patent No. 390,051, dated September 25, 1888.

Application filed June 5, 1888. Serial No. 276,100. (No model.)

To all whom it may concern:

Be it known that I, ALOIS ALLMUTH, of the city, county, and State of New York, have invented certain new and useful Improvements 5 in Pedal Reed-Organ Attachments for Pianos and Organs, of which the following is a specification.

This invention relates to an improved pedal reed-organ attachment for pianos and organs, 10 which is to be conveniently used by organists and students of the organ in connection with a piano or reed-organ, either for practicing at home or for combining the effects of the piano with the bass tones of an organ; and the invention consists of a pedal reed-organ attachment for pianos and organs in which the bellows and reed-case are arranged in a seat-frame, the bellows being worked by a hand-lever or other suitable power, while the reed- 15 valves are operated by fulcrumed levers, while intermediate pedal-levers provided with slide-pieces having abutments and wedge-pieces serve to operate the stop of said reeds, so as to open or close either set or both sets of reeds, 20 as desired.

In the accompanying drawings, Figure 1 represents a side elevation with a part broken away, showing my improved pedal reed organ attachment in position for use with an upright piano. Fig. 2 is a plan of the attachment, partly in horizontal section on line *x x*, Fig. 1, of the seat-frame of the attachment, showing the pedals and mode of operating the same; and Fig. 3 is a vertical longitudinal 35 section of the seat-frame on line *y y*, Fig. 1, showing the bellows, reed-case, and stop-valves. Fig. 4 is a vertical transverse section of the attachment on line *z z*, Fig. 2; and Fig. 40 5 is a vertical transverse section on line *k k*, Fig. 2, showing one of the pedal-levers for operating the stops of the reeds.

Similar letters of reference indicate corresponding parts.

In the drawings, A represents the base-frame 45 of my improved pedal reed-organ attachment for pianos and organs. At the front part of the base-frame A are arranged a number of pedals, B B, which are fulcrumed to a common pivot-rod, *b*, supported in lugs *b'* of the base-frame 50 A. To the rear end of the base-frame A is applied the seat-frame C, at the interior of which are located the reed-case D, wind-chest

D', bellows E E', and the wind-regulating bellows F, as shown in Figs. 3 and 4.

The pedals B B engage short intermediate levers, B', which are fulcrumed to a common pivot-rod, *d*, that is supported by lugs *d'* of the base-frame A, the rear ends of the fulcrumed levers B' engaging the front ends of the hinged and spring-actuated reed-valves D', as shown clearly in Fig. 4. By depressing the pedals B the reed-valves D' are opened and the reeds sounded.

The bellows E E' are arranged, respectively, above and below a horizontal partition, C', of the seat-frame C, the movable side walls of the bellows being connected by a pivot-rod, *e*, which passes through an opening, *e'*, in the partition C', so that when the bellows E are operated by a hand-lever, E'', or by a suitable motor connected to the lever, the bellows E and E' are alternately expanded or contracted, so as to alternately supply compressed air through the channels *e* to the wind-chest D' of the reed-case D, the surplus of air being taken up by the regulating-bellows F, which are arranged on top of the wind-chest D' and acted upon by spiral springs *f*, which are interposed between the movable side wall of the bellows F and the partition C', as shown in Fig. 3.

The regulating-bellows F are stopped by a stop, *f'*, when expanded to their full extent, and serve for the purpose of keeping up the regular and continuous supply of air to the reed-valves when playing the organ attachment. The operating-lever E'' of the bellows E E' is guided in a suitable manner and extended through a slotted opening, *e''*, in the end wall of the seat-frame C to the outside of the same, so that it may be worked either by hand or by a treadle, or by a motor whenever the reed-organ attachment is desired to be used.

If the bellows are to be operated by a motor, 95 the latter is arranged at one end of the seat-frame C, and connected by a pitman in the usual manner to the lever E'', so as to produce the proper working of the bellows.

Intermediately between the pedals B are arranged pedal-levers P P', which are pivoted at their front ends, and which serve for the purpose of opening or closing the stops of the reeds, of which, preferably, two are ar-

ranged—an eight and a sixteen foot stop. The eight-foot stop is opened or closed by the pedal-levers P P at one side of the attachment, while the sixteen-foot stop is operated by the pedal-levers P' at the other side of the same. The pedal-levers P P' are each provided with a slide-plate, p, which is guided on the pedal-levers and provided with an abutment, p^x, and with a wedge-piece, p', back of said abutment, the tapering end of which extends under a fixed yoke-piece, p², of the base-frame A, so that when the slide-plate p is pushed backward by the pressure of the foot on the abutment p^x the thinner end of the wedge-piece p' is moved under the fixed piece p², and the pedal-lever thereby retained in lowered position.

The pedal-levers P or P' are connected by rods p⁴ with stop-valves p⁵ in the wind-chest, so that either the eight or sixteen foot stop can be opened, or both, when both levers P P' are depressed. On depressing the pedals B the reeds are sounded as the necessary wind is admitted from the wind-chest to the reed-case. On releasing the wedge-piece p' from the fixed piece p² the stop-valve is closed again. In this manner either one or both stops may be opened or closed as required by the player.

The attachment is independent of and not connected with the piano or organ with which it is to be used, so that it can be removed after use and put aside, or moved up to the piano or organ when required for use. As the reed-case and bellows are arranged in the seat-frame, no extra space is taken up by the same, while they are also out of sight.

The attachment can be used with any style of piano or organ, and forms a comparatively cheap and convenient device, by which not only the organist and students of the organ can practice at home, but by which also the effects of a piano or reed-organ can be blended with the bass tones of an organ in a very effective and attractive manner. It can also be used for accompanying orchestral instruments, as it supplies the full bass tones for the same, it being portable and readily taken to the place where it is to be used.

Having thus described my invention, I claim as new and desire to secure by Letters Patent-- 50
1. The combination, in a pedal reed-organ attachment for pianos and organs, of a series of pedals, reed-valves operated thereby, a reed-case, a wind-chest for said reed-case, pedal-levers located between the pedals and provided with setting devices, stop-valves in said wind-chest, and connecting-rods between said pedal-levers and stop-valves, substantially as set forth. 55

2. The combination of a series of fulcrumed 60 pedals, intermediate levers, reed-valves operated by said levers, a reed-case containing the reeds, a wind-chest above the reed-case, intermediate pedal-levers provided with slide-plates and wedge-pieces, valves in said wind-chest, and connecting-rods between the pedal-levers and valves, substantially as set forth. 65

3. In a pedal reed-organ attachment for pianos and organs, the combination, with the pedal-levers P, provided with slide-plates 70 p, having projecting abutments p^x and wedge-pieces p', of yoke-shaped pieces p², located at the rear of the wedge-pieces, stop-valves p⁵, located in the wind-chest, and pivot-rods connecting the pedal-levers and stop-valves, substantially as set forth. 75

4. In a pedal reed-organ attachment for pianos and organs, the combination of a supporting base-frame, a series of pedals pivoted to said frame, a seat-frame supported on said base-frame, reed-valves operated by the pedals, a reed-case, wind-chest and bellows located in the seat-frame, stop-valves in the wind-chest, pedal-levers provided with setting devices, and connecting-rods between the pedal-levers and stop valves, substantially as set forth. 85

In testimony that I claim the foregoing as my invention I have signed my name in presence of two subscribing witnesses.

ALOIS ALLMUTH.
